(57) **CLAIM**

The ornamental design for a film dispenser, as shown and described.

DESCRIPTION

FIG. 1 is a front top perspective view of a film dispenser showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front perspective view thereof, shown in an environment thereof.

The broken lines in the middle of the film dispenser in FIG. 8 depict the environment thereof and form no part of the claimed design; the broken lines elsewhere in the drawings illustrate portions of the film dispenser that form no part of the claimed design.
